UNITED STATES PATENT OFFICE

THOMAS H. GOLDEN, OF POTTSVILLE, PENNSYLVANIA, ASSIGNOR TO PHILLIPS-JONES CORPORATION, OF NEW YORK, N. Y., A CORPORATION OF NEW YORK

SHIRT PACKAGE

Application filed December 12, 1932. Serial No. 646,809.

This invention relates to packages for garments, such, for example, as men's shirts. In packaging such products it is important that they be neatly folded so as to present an attractive appearance, and it is desirable to so fold the sleeves of the garment that the cuffs will be permitted to lie on the face of the body of the garment where they will be exposed to view. This is particularly desirable where 10 the garment is enclosed in a transparent wrapping material, such as cellophane, glassine, or the like, because the exposure of the cuffs so as to show their style and construction has a tendency to prevent the prospective purchaser from destroying the wrapping in order to get at the interior of the package.

Furthermore, it has heretofore been the practice in packaging men's shirts to provide a label containing, for example, the maker's 20 name and the style of the shirt, and to place this label on a paper band which was wrapped about the body of the folded shirt with its ends secured together at the back of the package by paste, by pinning, or by some other 25 convenient means.

In order to hold the cuffs properly in position on the front of the shirt it has heretofore been customary to fasten each cuff to the 30 front of the shirt by pinning, and then to place the paper band containing the label about the shirt and fasten its ends together at the back. Two operations are thus required after the folding of the shirt is completed to prepare it to receive the transparent 35 wrapper, if such is used, and these operations are an appreciable factor in the cost of packaging the shirt.

It is the principal object of my present invention to devise a shirt package wherein the 40 cuffs are held in place on the front of the shirt without fastening them to the shirt bosom, and the label is held in position without the use of a band encircling the shirt.

Another object of the invention is to provide a device carrying the label which can be 45 quickly applied to the cuffs for holding them in position, thereby eliminating both of the operations above referred to and substituting 50 therefore a single operation which requires

less time than either of the former operations.

Another object of the invention is to provide a device for maintaining the cuffs in stretched flat condition so as to improve the 55 appearance of the package.

A further object of the invention is to prevent the cuffs from being displaced during the operation of wrapping the garment with wrapping material, without pinning the cuffs 60 to the shirt.

My invention will be understood from a consideration of the accompanying drawing, illustrating by way of example the present preferred embodiment of the invention, and 65 by reference to the following description in connection with the drawing. In the drawing

Fig. 1 is a front or plan view of a complete shirt package arranged in accordance with 70 my invention;

Fig. 2 is a plan view of the device for holding the cuffs in place;

Fig. 3 is a transverse section taken on line 3—3 of Fig. 1, looking in the direction of the 75 arrows;

Figs. 4 and 5 are views similar to Fig. 3 illustrating two modifications; and

Fig. 6 is a transverse section taken through a single cuff.

Referring now to Figs. 3 and 1, the shirt is folded with the bosom 1 in front of or on top of a rectangular form 2 consisting, for example, of a sheet of cardboard, the lower portions of the shirt and the shirt sleeves being folded neatly on the back of form 2 and pinned into position. The cuffs 3 and 4 are arranged with their outer edges 5 and 6 substantially in alignment with the outer edges of the shirt bosom, the portions 7 and 8 of the sleeves immediately adjacent the cuffs forming hinges which permit the cuffs to lie flat against the front of the shirt. The cuffs, however, are not pinned to the shirt bosom as customary, and if the package as shown in 90 Fig. 1, prior to the application of the envelope 9 of transparent wrapping material, were turned upside down, the cuffs would hang down vertically from the sides of the shirt. Cardboard form 2, preferably has a projec- 100

tion at the top, as shown, for supporting the collar. It is also preferably cut away at the lower corners, as shown, to permit the cuff buttons to sink into the soft folds of the shirt 5 and prevent bulkiness when a number of shirts are stacked upon one another.

The cuffs are arranged in alignment as shown in Fig. 1 and the device 10 is inserted with one end thereof in each cuff. Device 10 10 comprises a strip of sheet material such as paper or cardboard having end portions 11 and 12 which are of a width equal to or slightly greater than the inside dimension of the flattened cuffs so that when the device is inserted in the cuffs these end portions will serve to stretch the surface of the cuffs somewhat and have a tendency to keep the cuffs in smooth condition. Such a reasonably snug fit between the end portions 11 and 12 and 15 the interiors of the cuffs is desirable also for the purpose of causing the end portions 11 and 12 to make a firm frictional engagement with the cuffs.

The central portion 13 of device 10 is preferably narrower than end portions 11 and 12, and may be made of about the width of the paper bands formerly employed. The length of the narrow portion 13 is sufficient so that when the device is in position neither of the 20 end portions 11 or 12 will be visible. The central portion 13 provides a suitable space for the reception of a label showing the name of the maker of the shirt and any other information desirable.

25 The frictional engagement of the end portions 11 and 12 within the cuffs 3 and 4, together with a certain amount of stiffness inherent in the device, causes the cuffs to be maintained in position on the front of the shirt during the handling or manipulation of the shirt in applying the transparent wrapper 9. Device 10 is also sufficient to maintain the cuffs in position without the use of the transparent wrapper 9, and the modification shown in Fig. 4 illustrates such a package. Also, if desired, as shown in the modification of Fig. 5, the form 2, as well as the transparent wrapper 9, may be omitted from the package. When the wrapper 9 is omitted, 30 however, it is preferable to make device 10 of somewhat heavier material than when the wrapper is used.

In making up the package the ends 11 and 12 are merely slipped into the cuffs 3 and 4 35 with the fingers. The end portions 11 and 12 may be bowed slightly by transverse pressure between thumb and forefinger on opposite side edges of the device. This reduces the distance between these two end portions and facilitates the entrance of the end portions into the cuffs. Afterwards the release of the end portions 40 allows them to spring back into position or to approximately flat position, and stretch the cuff smooth, as shown on a somewhat exaggerated scale in Fig. 6.

The insertion of the device 10 can be done in much less time than would be required to pin the two cuffs in place, or fasten the paper band about the shirt. After the device 10 is inserted in the cuffs, the shirt is turned over 70 so that the bosom 1 lies downward upon a sheet of wrapping material of the proper size and the wrapper is folded and secured in place. In turning the shirt over on the sheet of wrapping material, the device 10, even 75 when made of comparatively light weight paper is sufficient to prevent the cuffs from hanging down or flopping out of position.

It will be understood that the cuffs 3 and 4 do not necessarily have to be placed at the bottom of the shirt as shown in Fig. 1, but may be arranged near the top of the shirt, if desired.

80 My present improvement in shirt packages not only reduces the expense incident in preparing the shirts for sale, but renders the package particularly neat and distinctive.

85 It will be understood that variations in the package may be made within the scope of the appended claims.

90 I claim:

95 1. In a shirt package in which the shirt is folded flat with the front thereof exposed upwardly and the cuffs are buttoned and laid against the front of the shirt with the portions of the sleeves adjacent the cuffs extending around the side edges of the shirt, said cuffs lying with their open ends spaced and in alignment, the combination of a strip of sheet material having a body portion for receiving a label and end portions on each side thereof, said end portions 100 being respectively inserted in the cuffs and frictionally engaging the same to retain both strip and cuffs in position against the front of the shirt.

105 2. In a shirt package in which the shirt is folded about a support leaving the shirt displayed smoothly upon said support and the cuffs are buttoned and laid against the shirt front with the portions of the sleeves adjacent the cuffs extending around the side edges of the support, said cuffs lying with their open ends spaced and in alignment, the combination of a strip of sheet material having a body portion for receiving a label and end portions on each side thereof, said end portions 110 being respectively inserted within the cuffs and frictionally engaging the same to maintain both strip and cuffs in position 115 against the front of the shirt.

120 3. In a shirt package in which the shirt is folded about a support leaving the shirt displayed smoothly upon said support and the cuffs are buttoned and laid against the shirt front with the portions of the sleeves adjacent the cuffs extending around the side edges of the support, said cuffs lying with their open ends spaced and in alignment, the combination of a strip of sheet material having 125

a narrow body portion for receiving a label, and enlarged end portions on each side thereof adapted to be received within the open ends of said cuffs and of sufficient width to frictionally engage the folds of the cuffs, both strip and cuffs being thereby maintained in position against the front of the shirt.

4. In a shirt package in which the shirt is folded flat with the front thereof exposed upwardly and the cuffs are buttoned and laid against the front of the shirt with the portions of the sleeves adjacent the cuffs extending around the side edges of the shirt, said cuffs lying with their open ends spaced and in alignment, the combination of a strip of sheet material having a body portion for receiving a label and end portions on each side thereof, said end portions being respectively inserted in the cuffs and frictionally engaging the same to retain both strip and cuffs in position against the front of the shirt, and a wrapping of transparent material enveloping the package.

5. In a shirt package in which the shirt is folded about a support leaving the shirt displayed smoothly upon said support and the cuffs are buttoned and laid against the shirt front with the portions of the sleeves adjacent the cuffs extending around the side edges of the support, said cuffs lying with their open ends spaced and in alignment, the combination of a strip of sheet material having a body portion for receiving a label and end portions on each side thereof, said end portions being respectively inserted within the cuffs and frictionally engaging the same to maintain both strip and cuffs in position against the front of the shirt, and a wrapping of transparent material enveloping the package.

In testimony whereof I affix my signature.
THOMAS H. GOLDEN.
